FIG. 5.

INVENTOR—

Albert D. Grover,

by A. A. Thomas
Atty.

UNITED STATES PATENT OFFICE.

ALBERT D. GROVER, OF NEW YORK, N. Y., ASSIGNOR TO AUTOSALES CORPORATION, A CORPORATION OF NEW YORK.

VENDING-MACHINE.

1,385,822.

Specification of Letters Patent. Patented July 26, 1921.

Application filed May 8, 1918. Serial No. 233,194.

To all whom it may concern:

Be it known that I, ALBERT D. GROVER, a citizen of the United States, and a resident of New York, in the county of New York and State of New York, have invented certain new and useful Improvements in Vending-Machines, of which the following is a specification.

My invention relates to vending machines and has for its object the provision of a machine embodying certain improvements and advantages over machines of this class heretofore constructed.

My invention is particularly applicable to multiple-compartment vending machines of the large type—that is to say, those which are operated in public places, like streets, railroad stations, and the like. Each of the magazines of my new machine has associated therewith a hand-operable delivery mechanism. These mechanisms are mounted separately and independently of each other, so that each mechanism may be removed from the machine as a unit without disturbing the other delivery mechanisms. In this way, should any one of these separate delivery mechanisms get out of order, it is easily replaced by another. When these delivery mechanisms are in place on the machine, they form part of the front wall of the casing, and so dispense with the necessity of a separate outer plate to cover these mechanisms, as is found in many machines heretofore constructed.

Another object of my invention is to provide certain improvements in a coin-controlled delivery mechanism employing a slidable coin-plate and a plunger connected therewith.

The objects and advantages of my invention will become apparent from a detailed description of the accompanying drawings, in which—

Figure 1 shows a plan view of a portion of a vending machine embodying my invention;

Fig. 2 is a vertical section approximately on line 2—2 of Fig. 1, looking in the direction of the arrows;

Fig. 3 is a transverse cross-section through one of the delivery mechanisms approximately on line 3—3 of Fig. 1, looking in the direction of the arrows;

Fig. 4 is a vertical cross-section approximately on line 4—4 of Fig. 2, looking in the direction of the arrows toward the front of the machine;

Fig. 5 is a detached perspective view of the common frame-work which supports all of the delivery mechanisms, one of these mechanisms being shown in place on the frame-work; and

Fig. 6 is a cross-section on line 6—6 of Fig. 1, showing how the coin-plate ejects a coin under certain conditions.

The outer casing of the machine may be of any preferred construction. For lack of space, the entire casing is not indicated in the drawings, but only certain portions thereof. The side walls of the casing are shown in the drawings at 1 and 2. These side walls project forwardly at 3 so as to provide sufficient space to accommodate the delivery mechanisms. The grooves or channels 4 of the side walls 1 and 2 are adapted to receive the side members 5 of a supporting frame-work indicated as a whole by F and shown in perspective in Fig. 5. This frame-work preferably consists of a pair of transverse members 6 and 7 on which are rigidly mounted the side members 5 and the intermediate members 8. The number of intermediate members will, of course, depend upon the number of delivery mechanisms to be embodied in the machine. In the drawings I have illustrated a four-compartment machine, having four delivery mechanisms. The side members 5 are shown provided with bottom flanges 9 (see Fig. 4); through which pass suitable fastening devices, such as rivets 10 or the like, whereby the side members are rigidly mounted on the cross-pieces 6 and 7. These cross-pieces are preferably provided with upstanding flanges 11 and 12, which not only strengthen the cross-pieces, but assist in rigidly mounting the members 5 and 8 thereon. From Fig. 5 it will be seen that the members 5 and 8 are provided with notches 13 which firmly engage the flange 11 of the front cross-piece 6. At the rear, the members 5 and 8 abut against the upstanding flange 12 of the rear cross-piece 7. The members 8 are provided with bottom lugs 14 which enter corresponding openings in the cross-pieces 6 and 7, and by means of these lugs

14 the members 8 are securely riveted on to the cross-pieces 6 and 7. The frame-work F as a whole, is secured in place between the side walls of the casing by suitable fastening devices, such as screws 15, which pass through openings 16 in the front cross-piece 6 into the top of the lower front panel 17 of the casing. This is clearly shown in Figs. 2 and 4.

- 10 It will be seen from Figs. 4 and 5 that the members 5 and 8 of the frame-work F are provided with laterally projecting flanges which are arranged in pairs. These pairs of flanges are marked *a*, *b*, *c*, and *d*, respectively. Between each pair of these flanges, is mounted a delivery mechanism. In Fig. 4, the four delivery mechanisms are, as a whole, indicated respectively by A, B, C, and D. The delivery mechanism A is mounted between the flanges *a*, the mechanism B is mounted between the flanges *b*, and so on. As these four mechanisms are alike in construction, it will only be necessary to describe one of them.
- 15 Each delivery mechanism has a top plate indicated as a whole by P. This top plate consists of a horizontal front section 18, a horizontal rear section 19, an intermediate vertical section 20, and a downwardly extending front section 21. This plate is preferably formed of a single piece of sheet metal and is bent into the desired shape.

20 The top plate P of each delivery mechanism carries a casting indicated as a whole by E, which is formed with a pair of side grooves 22. By means of these grooves the delivery mechanism is adapted to be slid into place between a pair of flanges *a*, *b*, *c*, or *d*, on the main frame-work F. As clearly seen from Fig. 4, the flanges of the frame-work enter the grooves or channels 22 and thereby support the mechanism in firm position on the frame-work. The inward movement of the delivery mechanism is limited by the front section 21 of the top plate P engaging the front edges of the supporting members 5 and 8 of the frame-work. It will be seen from Fig. 4 that when the delivery mechanisms are in place on the frame-work F, the top plates P are contiguous, and so present practically a single outer plate which forms part of the outer casing of the machine.

25 The top plate P of each delivery mechanism is provided with a coin-entrance opening 23, which is in alinement with the coin-opening 23^a in the coin-slide 24. Through the vertical section 20 of the plate P projects a hand-operable plunger 24^a, to which the coin-slide 24 is rigidly connected. A 30 slideable block indicated as a whole by K is also rigidly connected with the plunger 24^a. This block is mounted to reciprocate between a pair of arms 25 projecting rearwardly from the plate P. These arms are

35 securely mounted on the plate P in any suitable manner, as by means of lugs 26 projecting through the top plate and serving as rivets. The arms 25 are provided with a pair of alined slots 27 in which 70 engage the cross-pieces 28 of the block K, as shown in Figs. 2, 3 and 5. The arms 25 are at their rear connected by a cross-member 29, on which rests the rear end of the rod 30 which carries the return spring 75 31. The arms 25 rest at their rear end on top of a suitable supporting member 32 rigidly mounted between the side walls of the casing.

80 The block K of each delivery mechanism has pivoted thereon a suitable ejecting member J. Associated with each delivery mechanism is a magazine M containing the goods or packages to be delivered. I prefer to mount the magazines directly on the arms 85 25 of each delivery mechanism, as shown in Fig. 2, where the arms 25 are shown provided with recesses 33 adapted to receive the projections 34 at the lower end of the magazine. It will, of course, be understood 90 that the upper end of each magazine is suitably held against tilting. In Fig. 2, the lowermost package in the magazine M is indicated at 35, and it will be seen that this package is above the normal position 95 of the ejecting member J. When the plunger 24^a is pushed in without a coin having been previously deposited, the ejecting member J is not sufficiently advanced to cause delivery of any goods. When, however, a proper coin is deposited in the coin-opening 23^a of the coin-slide 24 and the plunger 24^a is pushed in, the coin causes the normally locked coin-slide to be released 100 and the plunger is free to be operated to 105 its full extent. As a result, the pivoted ejecting member J is raised at its rear end so as to engage the bottom package 35 and push the same rearwardly out of the magazine, from where it drops down a delivery 110 chute to an opening at the front of the casing (not shown).

115 In view of the fact that the coin-controlled mechanism by which the ejector J is actuated into ejecting position through the medium of a proper coin does not form part of my present invention, I have not deemed it necessary to illustrate the same in detail, nor to describe the same. In the broad aspect of my invention, any suitable 120 delivery mechanism may be carried by each of the plates P. For the sake of convenience, I have herein shown certain coin-controlled features which form the subject-matter of the Romans & Grover Patent No. 125 625,123, dated May 6, 1899.

130 The features of novelty which I claim in the delivery mechanism herein shown, are: first, the means by which the slideable block K is prevented from being tilted upwardly

- by a downward pressure on the plunger 24^a; second, the means for causing the coin-slide 24 to eject a coin which is deposited when the coin-slide is out of normal position; third, the means for permitting removal of a deposited coin through the coin-entrance opening 23; and, fourth, guarding against the horizontal insertion of an instrument into the machine.
- 10 The upward tilting of the block K, which would cause elevation of the ejector J into ejecting position, is positively prevented by the cross-pieces 28 of the block engaging in the slots 27 of the arms 25. By virtue of 15 this construction, the block K is compelled to travel in a horizontal path.
- As shown in Fig. 6, the casting E of each delivery mechanism has secured thereto, by means of screws e, or otherwise, a member 20 indicated as a whole by E'. This member has a front extension f which forms practically a continuation of the front end of the casting E, and a depending rear extension g. The front section 21 of each plate P is 25 provided with a coin-discharge opening h. Should a coin be deposited through the coin-entrance opening 23 when the coin-slide 24 is in inner or actuated position, the coin will drop on to the top of the casting E.
- 30 When the coin-slide then returns forwardly to normal position, the front edge of the slide will push the coin (see H, Fig. 6) out of the machine through the opening h.
- The member E' is provided with an opening k, which is in alignment with the opening or cut-out portion k' of the casting E. The front section 21 of the plate P has an opening m. As seen from Fig. 6, the openings m, k, k', 23^a and 23, are in alignment, 35 so that an instrument may be inserted into the opening m to lift a deposited coin out of the opening 23, whenever the intending purchaser desires for some reason to get back his deposited coin. The depending extension g of the member E' is so arranged 40 as to prevent the insertion of an instrument horizontally into the machine, whereby tampering with the coin-controlled mechanism back of the guard g is effectively prevented.
- 45 The rear section 19 of the plate P of each delivery mechanism is provided with a lug 36 which coöperates with the lower end 37 of the upper front panel 38 of the casing to 50 lock the delivery mechanisms in place when the front panel 38 is in closed position. Only the lower portion of the front panel 38 is shown in the drawings, but it will be understood that this panel extends upwardly to the top of the machine to close 55 the space where the magazines are housed. It is usual to provide a lock at the upper end of the removable front panel 38, so that this panel may be locked in place on the 60 casing. The panel 38 is usually of wood,
- and the lower edge 37 is preferably a separate piece of metal secured to the wooden portion of the panel by means of screws 39, or otherwise. The panel 38 is also provided with a hook portion 40 adapted to engage pins or lugs 41 projecting inwardly from the side walls of the casing. It will be clear from Fig. 2 that when the upper front panel 38 is in place, the engagement between the parts 36 and 37 absolutely locks the delivery 65 mechanisms against withdrawal from the machine. Another advantage of this locking means between the delivery mechanisms and the upper front panel 38 is, that unless all of the delivery mechanisms are in proper 70 position on the frame-work F, the lower end 37 of the front panel 38 cannot rest on the rear section 19 immediately in front of the lugs 36, in which event it will be impossible to lock the panel 38 in place, because the upper end of the panel would not then go into the casing. I have not illustrated this particular point, because the use of removable front panels on vending machines is well known, and it will therefore be understood how the panel would not fit at the top of the casing if the lower end 37 rested on the lugs 36 instead of on the section 19 of the plates P.
- 75 It will be seen from the foregoing that I have provided a multiple-compartment machine in which the separate delivery mechanisms may be removed independently of each other. Should any one of the mechanisms require repair, it is only necessary 80 to remove that mechanism and insert a new one in its place. Heretofore, in multiple-compartment machines, it has been necessary to send the entire machine, or at least all of the delivery mechanisms, back to the 85 factory for repair, when any one of those mechanisms became disarranged. By my present invention, I obviate this expensive procedure, for the local agent in charge of the machines will carry several extra mechanisms in stock, and it would be a simple matter to remove a defective mechanism and replace it by a good one.
- 90 When the delivery mechanisms are in place on the machine, the plates P act as a single member to close the opening between the lower end 37 of the upper front panel 38 and the top of the lower panel 17. This dispenses with a separate cover plate found in so many machines heretofore constructed.
- 95 Although I have herein shown and described a certain specific construction, I would have it understood that this has been merely for the sake of illustration and not by way of limitation. It is obvious that 100 changes may be made in the particular structure set forth, without departing from the invention as defined in the appended claims.
- 105 Having thus described my invention, 110

what I claim as new and desire to secure by Letters Patent of the United States, is:

1. In a vending machine, a closed outer casing having a plurality of magazines, a removable front panel on said casing, a main framework supported between the sides of the casing below said front panel, said main framework being provided with pairs of supporting rails or flanges running parallel with the sides thereof, each pair of said flanges being in alinement with one of said magazines, a unitary framework supported between each pair of said flanges, each of said unitary frameworks being readily slidably into and out of engagement with the flanges of said main framework independently of the other unitary frameworks, hand-operable delivery mechanism carried by each of said unitary frameworks, each of said unitary frameworks and its delivery mechanism being removable as a single member or unit without disturbing the other unitary frameworks and their delivery mechanisms, and coöperating means on said unitary frameworks and the lower end of said front panel for locking all of said unitary frameworks in place on said main framework when said panel is in closed position, said unitary frameworks being automatically unlocked upon the removal of said panel.
2. In a vending machine, a closed outer casing having a plurality of magazines, a removable front panel on said casing, a main framework supported between the sides of the casing below said front panel, said main framework being provided with pairs of supporting rails or flanges running parallel with the sides thereof, each pair of said flanges being in alinement with one of said magazines, a unitary framework supported between each pair of said flanges, each of said unitary frameworks including a top plate which is readily slidable into and out of engagement with a pair of said flanges independently of the other unitary frameworks, the top plates constituting a portion of the outer front wall of said casing below said removable panel, hand-operable delivery mechanism carried by each of said unitary frameworks, each of said unitary frameworks and its delivery mechanism being removable as a single member or unit without disturbing the other unitary frameworks and their delivery mechanisms, and coöperating means on said unitary frameworks and the lower end of said front panel for locking all of said unitary frameworks in place on said main framework when said panel is in closed position, said unitary frameworks being automatically unlocked upon the removal of said panel.
3. In a vending machine, a closed outer casing having a plurality of magazines, a removable front panel on said casing, a main
- framework supported between the sides of the casing below said front panel, said main framework being provided with pairs of supporting rails or flanges running parallel with the sides thereof, each pair of said flanges being in alinement with one of said magazines, a unitary framework supported between each pair of said flanges, each of said unitary frameworks comprising a top plate and a pair of arms extending rearwardly from said top plate, said top plates being readily slidable into and out of engagement with said flanges independently of each other and constituting a portion of the outer front wall of said casing below said removable panel, means for supporting a magazine on each pair of said arms, hand-operable delivery mechanism carried by each unitary framework, said delivery mechanisms including each a hand-operable member projecting forwardly from the top plate of the associated unitary framework, an ejecting member movable between the pair of arms of each unitary framework, each of said unitary frameworks and its delivery mechanism being removable as a single member or unit without disturbing the other unitary frameworks and their delivery mechanisms, and coöperating means on said top plates and the lower end of said front panel for locking all of said unitary frameworks in place on said main framework when said panel is in closed position, said unitary frameworks being automatically unlocked upon the removal of said panel.
4. In a vending machine, a casing having an upper section and a lower or base section, a removable panel for closing the front of said upper section, a front panel for said base section, a framework mounted between the sides of said base section at the upper end of said second panel, a plurality of metal plates mounted side by side on said framework and closing the space or gap between said two panels, said plates being slidably supported and removable independently of each other, a hand-operable delivery mechanism carried by each plate and removable therewith, and coöperating means on said plates and the lower end of said removable panel for locking said plates in position on said framework when said removable panel is in closed position.
5. In a vending machine, a casing, a framework supported between the sides of said casing and removable as a whole, said framework comprising a transverse supporting base and a plurality of flanged members rigidly mounted on said base at right angles thereto, the flanges of said members being arranged in pairs and the flanges of each pair extending toward each other, a unitary section slidably supported between each pair of flanges, delivery mechanism mounted on each section, each section and its delivery

framework supported between the sides of the casing below said front panel, said main framework being provided with pairs of supporting rails or flanges running parallel with the sides thereof, each pair of said flanges being in alinement with one of said magazines, a unitary framework supported between each pair of said flanges, each of said unitary frameworks comprising a top plate and a pair of arms extending rearwardly from said top plate, said top plates being readily slidable into and out of engagement with said flanges independently of each other and constituting a portion of the outer front wall of said casing below said removable panel, means for supporting a magazine on each pair of said arms, hand-operable delivery mechanism carried by each unitary framework, said delivery mechanisms including each a hand-operable member projecting forwardly from the top plate of the associated unitary framework, an ejecting member movable between the pair of arms of each unitary framework, each of said unitary frameworks and its delivery mechanism being removable as a single member or unit without disturbing the other unitary frameworks and their delivery mechanisms, and coöperating means on said top plates and the lower end of said front panel for locking all of said unitary frameworks in place on said main framework when said panel is in closed position, said unitary frameworks being automatically unlocked upon the removal of said panel.

framework supported between the sides of said casing and removable as a whole, said framework comprising a transverse supporting base and a plurality of flanged members rigidly mounted on said base at right angles thereto, the flanges of said members being arranged in pairs and the flanges of each pair extending toward each other, a unitary section slidably supported between each pair of flanges, delivery mechanism mounted on each section, each section and its delivery

mechanism being removable from said framework independently of the other sections and their delivery mechanisms, and means for locking said sections in place on 5 said framework.

6. In a vending machine, an outer casing, a plurality of magazines mounted therein, a main framework supported between the sides of said casing and having pairs of flanges running substantially parallel with the sides of the casing, a unitary framework supported between each pair of said flanges substantially in alinement with one of said magazines, parts of said unitary frameworks 10 constituting a portion of the outer wall of said casing, and a delivery mechanism carried by each unitary framework, each of said unitary frameworks and its delivery mechanism being removable from and insertible into said main framework as a single member or unit without disturbing the other unitary frameworks and their delivery mechanisms.

7. In a vending machine, an outer casing, 25 a plurality of magazines mounted therein, a main framework supported between the sides of said casing and having pairs of flanges running substantially parallel with the sides of the casing, a unitary framework supported between each pair of said flanges substantially in alinement with one of said magazines, each of said unitary frameworks having a top plate readily slidable into and out of engagement with the associated pair 30 of flanges independently of the other top plates, said top plates constituting a portion of the outer front wall of said casing, and a delivery mechanism carried by each unitary framework, each of said unitary frameworks 35 and its delivery mechanism being removable from and insertible into said main

framework as a single member or unit without disturbing the other unitary frameworks and their delivery mechanisms.

8. In a vending machine, an outer casing, 45 a plurality of magazines mounted therein, a main framework supported between the sides of said casing and having pairs of flanges running substantially parallel with the sides of the casing, a unitary framework 50 supported between each pair of said flanges substantially in alinement with one of said magazines, a delivery mechanism carried by each unitary framework, each of said unitary frameworks and its delivery mechanism being removable from and insertible into said main framework as a single member or unit without disturbing the other unitary frameworks, their delivery mechanisms, parts of said unitary frameworks 55 constituting a portion of the outer wall of said casing, a removable front panel on said casing, and coöperating means on said panel and said unitary frameworks for locking the latter on said main framework when said 60 panel is in closed position on said casing.

9. In a vending machine, a casing having an upper section and a forwardly projecting lower or base section, a panel for closing the front of each section, a plurality of metal 70 plates arranged side by side and completely closing the space or gap between the lower end of the upper panel and the top end of the lower panel, means for slidably supporting each plate independently of the others, 75 delivery mechanism carried by each plate and removable therewith, and means for locking said plates in position on the casing.

In witness whereof I hereunto subscribe my name this 4th day of May, 1918.

ALBERT D. GROVER.
